LINER WASHER

Filed Jan. 12, 1934

UNITED STATES PATENT OFFICE

2,042,817

LINER WASHER

John A. Wilcox, Huntington Beach, Calif.

Application January 12, 1934, Serial No. 706,380

6 Claims. (Cl. 166—20)

This invention relates to a washer for liners, perforated pipes, or the like, when said parts are positioned in a well.

An object of my invention is to provide a washer, the two spaced rubber rings of which can be expanded and collapsed at any desired point in the well.

A further object is to provide a washer which will pass freely into and out of the well, due to the fact that the rubber packers or rings are collapsed except when the tool is in operative position.

Another object is to provide a novel means of controlling the passage of fluid thru the tool, i. e., the passage is open when the tool is being run into or out of the well, and is closed when the tool is in operation, so that a washing action occurs thru the perforations or around a liner.

An advantage of my tool is that the rubber packers or rings can be long, thus providing a large bearing surface against the wall of the well which increases the effective life of the packers and also permits them to expand and collapse more effectively.

25 A further object is to provide a tool of the character stated which can be successively operated at various points in the well without withdrawing same to the surface.

30 A further object is to provide a tool of the character stated which is simple and effective in operation and which will more thoroughly wash the perforations in the pipe or the liner.

Other objects, advantages and features of invention may appear from the accompanying drawing, the subjoined detailed description, and the appended claims.

In the drawing:

Figure 1 is a longitudinal sectional view of my tool with parts thereof shown in elevation.

40 Figure 2 is a sectional view taken on line 2—2 of Fig. 1.

Figure 3 is an enlarged fragmentary longitudinal sectional view of the valve assembly.

45 Figure 4 is a sectional view taken on line 4—4 of Fig. 1.

Referring more particularly to the drawing, the numeral 1 indicates a pipe or liner which has a series of holes 2 extending thru the wall thereof, said holes being washed or cleaned by the tool, as will be further described.

50 My washer comprises a head or coupling 3 which is threaded as at 4 to receive the drill pipe or tubing. A ring 5 screws into the bottom of the coupling 3 and the bottom surface of this ring is

shaped so as to fit on the top of the rubber packer 6.

A mandrel 7 fits against the bottom of the packer 6, and this mandrel is provided with a plurality of slots 8 which extend horizontally therethru. A joint 9 screws onto the bottom of the mandrel 7 with a straight thread so that wear can be taken up in the packers. The joint 9 is also provided with a plurality of elongated slots 10. The circulating fluid passes out of the slots 10 5 and 10, and thence thru the perforations in the pipe, as will be further described.

A lower rubber packer 11 fits against the bottom of the joint 9, and a ring 12 fits against the bottom surface of the packer 11.

15 A sub 13 screws onto the bottom of the ring 12 and this sub is so constructed as to hold the valve seat, as will be further described.

A coupling 14 screws into the lower end of the sub 13, and clamps a seat 15, in position. The 20 seat 15 is held between the top of the coupling 14 and an inwardly projecting ring 16 on the sub 13. A fitting 17 screws onto the coupling 14, and in turn, receives the threaded shank of a spear 18, of usual and well known construction, 25 as disclosed in Patent No. 1,751,090, issued March 18, 1930. The spear 18 is so arranged that it will engage the liner or pipe against downward pressure of the tool, i. e., the slips 19 of the spear 30 bite into the pipe or liner, thus holding the tool against downward movement. The spear can be released in the usual and well known manner so that the tool can be raised or lowered any desired distance and again set, so as to wash the liner or perforations.

35 A tube 20 fits on the inside of the tool and extends substantially the length thereof. A flange 21 at the upper end of the tube is splined or grooved as shown at 21a and fits into corresponding splines or grooves in the head 3. Thus, the 40 tube can move longitudinally but cannot rotate relative to the outer part of the tool. Holes 22 are provided in the tube 20 opposite the slots 8. The circulating fluid can thus pass outwardly thru the holes 22, thence into the slots 8 or 10, 45 thereby washing the liner or perforations.

The lower end of the tube has a collar 23 screwed onto it, and this collar carries a valve 24. The valve is held in a spider so that the circulating fluid can pass around the edges of the valve 50 when the sleeve 20 is raised. In lowered position, the valve 24 rests on the seat 15, thus closing the longitudinal passage thru the tool and compelling the circulating fluid to pass outwardly thru slots 8 and 10 to wash the liner or perforations. The 55

collar 23 also has a splined connection, as shown at 25, with the sub 13, thereby preventing relative rotation between the tube and the balance of the tool.

5 When the tool has been lowered on the drill pipe to the desired point, the spear 18 is set, thus preventing further downward movement of the tool. Weight is then exerted on the drill pipe which causes the packers 6 and 11 to compress 10 and also to bulge outwardly against the casing i. e., the packers are set. A tight seal is thus provided at the top and bottom adjacent the slots 8 and 10. The compression of the packers telescopes the tool, thus pressing the valve 24 against its seat 15. While the tool was being run into the hole, the valve 24 was off its seat, thus permitting the circulating fluid to move longitudinally thru the tool. When the packers are expanded, this free longitudinal movement of the 15 circulating fluid is stopped and the fluid is caused to by-pass outwardly thru the slots 8 and 10, thence thru the perforations 2, to thoroly clean 20 said perforations.

When weight is taken off the drill pipe it is 25 rotated and an upward pull exerted, in order to release the spear 18, the packers 6 and 11 will be collapsed and simultaneously, the valve 24 will be lifted from its seat. Circulation thru the perforations is thus stopped, and the tool is moved to 30 another point where the operation is repeated.

Another object in unseating the valve prior to moving the tool is that the pressure is equalized on the inside and outside of the tool and also on both the top and the bottom of the packers. 35 When this has been accomplished, the tool can be readily moved without danger of injuring the packers, i. e., when the pressures are equalized, the packers will not be forced against the wall of the well, and will therefore readily release or 40 collapse and allow the tool to be moved.

Having described my invention, I claim:

1. In a liner washer, a pair of spaced packers in the washer, a spear attached to the washer, said washer having openings therethru between 45 the spaced packers, said washer being longitudinally collapsible, said packers being adapted and arranged to be compressed and expanded, when the washer is collapsed, whereby a seal is provided on each side of the openings, a fluid conduit extending longitudinally in the washer, said conduit having openings therein aligned with the first named openings, a closure means in the conduit below said openings, said closure means being closed on expansion of the packers.

2. In a liner washer, a pair of spaced packers on the washer, a spear attached to the washer, said washer having openings therein between the spaced packers, said washer being longitudinally collapsible, said packers being adapted to be 5 compressed and expanded, when the washer is collapsed, whereby a seal is provided on each side of the openings, a valve means in the washer, and means operably connected to the valve means whereby said valve means is closed when the 10 packers are expanded.

3. In a washer including a pair of spaced packers, said washer having a plurality of openings arranged between said packers, a spear attached to the washer, said spear being adapted to prevent downward movement of the washer, a tube 15 extending longitudinally in the washer, a valve on the tube, a valve seat in the washer, said valve being seated when weight is applied to the washer to compress the packers.

4. In a washer including a pair of spaced packers, said washer having a plurality of superposed openings therein, said openings being positioned between the packers, a tube within the washer, said tube having holes therein opposite said 25 openings, means non-rotatably holding the tube within the washer, a valve on the lower end of the tube, a valve seat in the washer, a spear attached to the washer, said valve being adapted to rest on the seat when weight is applied to the 30 washer to compress the packers.

5. In a liner washer including a pair of spaced packers, said washer having a plurality of openings between the packers, a tube within the washer, said tube having holes therein opposite 35 said openings, a splined connection between the tube and the washer, a valve on the lower end of the tube, a seat in the washer below the valve, said valve being adapted to engage the seat when the packers are expanded, thereby forcing fluid 40 thru the holes and openings, a spear on the washer, said spear holding the body against downward movement when set.

6. A telescoping liner washer, a pair of spaced packers, means coupling the packers, said washer 45 having openings therein between the spaced packers, a tube within the washer, said tube having holes therein opposite said openings, valve means in the washer operably connected to the tube, a spear attached to the washer, said valve 50 means being closed and the packers expanded when the washer is telescoped.

JOHN A. WILCOX.
